George K. Canias
BY
Joshua R. Stork
HS ATTORNEY

UNITED STATES PATENT OFFICE.

GEORGE K. CANIAS, OF PHILADELPHIA, PENNSYLVANIA.

BILLIARD CUE.

Application filed October 16, 1924. Serial No. 743,893.

To all whom it may concern:

Be it known that I, GEORGE K. CANIAS, a citizen of Greece, having declared my intention of becoming a citizen of the United States, residing at Philadelphia, in the county of Philadelphia and State of Pennsylvania, have invented certain new and useful Improvements in Billiard Cues, of which the following is a specification.

10 My invention relates to billiard cues and its objects are to provide a cue with a tip holder on which a tip may be quickly applied to fit neatly without gluing or trimming; to provide a tip which, when worn, 15 may be quickly removed, and to provide a tool for removing the tip.

These objects, and other advantageous ends which will be described hereinafter, I 20 attain in the following manner, reference being had to the accompanying drawing in which

Figure 1 is a fragmentary side elevation of a cue having my invention applied thereto,

25 Figure 2 a section on line 2—2 of Figure 1, and

Figure 3 a view similar to Figure 2 illustrating how the worn cue tip is removed.

Referring to the drawings, 1 indicates a 30 cue having a reduced part 2 and a beveled shoulder 3. A tip holder 4, of metal or other sufficiently strong material, has a solid part 5 and a cue cup 6 on the lower end of the solid part fitting over reduced part 2 and 35 having its edge 7 beveled and abutting the beveled shoulder 3. The holder has a stem 8 preferably threaded and fixed to the solid part, which is screwed into a hole in the end of the cue to secure holder 4 thereto. The 40 threaded stem is preferably coated with glue 9 to prevent it from unscrewing. A cup 10, integral with the upper end of the holder, receives a tip 11. The tip has a reduced part 12 which fits tightly within the cup and 45 abuts its bottom 13. A shoulder 14, formed by making reduced part 12, abuts the edge of cup 10. The outer surface 15 of the tip is flush with the outer surface 16 of the holder. A hole 17 is provided in the bottom 50 of the tip for receiving a removing tool

18 when the tip is worn to the hole as shown in Figure 3.

To renew a tip after it is worn from the dot-and-dash line position to the hole shown in the full line position in Figure 3, tool 18 is screwed into the hole and the tip pulled out of cup 10. A new tip of the proper size is forced into cup 10 so that its reduced part 12 will fit tightly against the side walls and abut the bottom of the cup, and the shoulder 60 14 on the tip will abut the edge of the cup. The depth of cup 10 is such that the tip therein will not be forced out by a sidewise knock. I have found from actual practice that the depth shown, which is substantially 65 one half the diameter of the cup, is sufficient to securely hold the tip in place.

With the holder and tip above set forth, a tip may be quickly renewed without gluing, or trimming its sides to make it flush 70 with the holder as is necessary with tips now in use. Abutting the tip against the bottom of the cup provides a solid base for the tip which prevents the tip from becoming loose and deformed while in use.

75 While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claims.

Having thus described my invention, what 80 I claim as new and desire to secure by Letters Patent is:—

1. In combination with a cue, having a cup on its upper end, of a tip fitting within the cup and having a hole in its bottom whereby, 85 when the tip is worn to the hole, a tool may be secured therein and the tip removed.

2. In combination with a cue having a reduced part and a bevelled shoulder at the base of said reduced part, of a holder having 90 a solid part and a cup on the lower end of the solid part fitting over the cue reduced part, the lower edges of said cup being bevelled to fit the bevelled shoulder, there being also a 95 cup at the upper end of said holder; and a 100

tip having a reduced part to fit the cup at the upper end of said holder, there being a hole in the bottom of said tip whereby, when the tip is worn to the hole, a tool may be secured therein and the tip removed.

3. In combination with a cue; a tip holder secured on the end of the cue and having a cup on its upper end, and a tip fitting within

the cup and having a hole in its bottom whereby, when the tip is worn to the hole, ¹⁰ a tool may be secured therein and the tip removed.

In testimony whereof I have signed my name to this specification.

GEORGE K. CANIAS.
